INDUSTRIAL TRUCK

Elmer J. Dunham, Battle Creek, Mich., assignor
to Clark Equipment Company, Buchanan,
Mich., a corporation of Michigan

Application December 11, 1937, Serial No. 179,273

12 Claims. (Cl. 214—113)

This invention relates to industrial trucks, and more particularly is directed to industrial trucks of the high lift type for use in shops, warehouses, loading docks and the like. This type of truck is especially adapted for material handling service, and for storing and tiering material or stock in industrial and mercantile establishments.

In the preferred form of the present invention I employ a gasoline powered tractor or truck unit capable of rendering continuous service without the necessity of recharging batteries or the like, as is the case with the electrically powered units.

One of the main advantages of the present construction is the provision of a standard power plant, chassis and frame with means for converting the unit into either a straight lifting and tiering unit, or a tilting and tiering unit, or telescoping tiering unit for extremely high lifting, which latter unit can be either of the tilting or non-tilting type.

In connection with the present invention, I preferably provide hydraulic mechanism for raising and lowering the load supporting means, which is operated from the power plant of the unit, and is under the direct control of the operator who is so disposed as to have a clear view of all operations and movements of the unit.

One of the features of the present invention is the disposition of the power unit and the operator's platform at the rear end of the frame whereby an effective counter-balance of considerable weight may be provided with a relatively long lever arm with respect to the fulcrum point of the load. This, in connection with suitable bracing members pivotally mounted on the rear portion of the frame and connected to the top of the upright members which form the guides and supports for the load-carrying means, provides a construction having a large factor of safety and protecting the operator from any possible hazards incident to overloading of the unit.

I have found that the placing of the drive wheels at the forward end of the frame adjacent the load supporting uprights serves to increase the tractive power of the unit, and also materially assists in controlling the movements of the unit when under full load. This arrangement also enables the uprights to be secured to the axle housing enclosing the drive transmitting means in such a manner that it may be removed with facility for repair or replacement of the upright structure or the load supporting means without necessitating the dismantling of any portion of the frame or chassis of the vehicle. Thus, possible damage or breakage of any of the tiering

mechanism requires only the replacement of such mechanism without in any manner affecting the frame and power unit of the vehicle.

Preferably, the dirigible steering wheels are located at the rear of the truck beneath the power unit, facilitating steering action at slow speeds under full load, and also allowing for close operations and for moving of the truck into positions so that the load can be discharged from a center aisle to machines or storage bins without requiring the truck itself to be moved completely out of the aisle.

Another distinct advantage arising from this location of the steering means resides in the ability to obtain a greater turning angle, thus reducing the turning radius of the truck without any loss of tractive effort. Thus the truck is able to turn at intersecting aisles which have a width less than the actual turning radius of the truck itself.

While the truck unit of the present invention is adapted to have any type of load supporting means mounted thereon for tiering movement, the present construction discloses the type of load-carrying means known to the trade as "finger" or "forklift" unit. This type of unit has forwardly projecting finger members which can be lowered to the ground level for insertion under boxes or crates resting on the floor, or for movement under skids or other similar bins or containers. By using such a finger lift, odd shaped packages or skids having varying widths and rack arrangements can be conveniently handled. In connection with such load-supporting means, I also provide for lateral adjustment of the fingers and for novel supporting means which effectively transfers the load to the uprights and the frame.

Still another advantage of the present construction resides in the provision of means responsive to the movement of the load supporting means into either of its limiting positions for automatically tripping the lift control lever into neutral position. This maintains the load-supporting means in either upper or lower raised position until such time as the control lever is again manually actuated by the operator. Automatic stop means of this type insures that the load-supporting means will not be forced beyond its limiting positions even if the operator should leave the truck unattended with the control lever in one of its operative positions. It is to be pointed out, however, that the control mechanism is so arranged that the load may be raised or lowered from any intermediate position, and no predetermined sequence of movement is necessary. This

places the load under the direct and instantaneous control of the operator so that the utmost maneuverability is obtained by the construction.

A further feature of the present invention resides in the provision of a brake mechanism which operates on the output shaft which transmits torque from the transmission to the drive axle. This takes the place of the usual brake mechanism at the driving wheels. In a preferred form of the invention this brake is of the type which is normally urged into braking position by heavy springs, and is released or moved into inoperative position by hydraulic means controlled by a foot treadle upon which the operator stands when it is desired to move the truck. If the operator should leave the truck, or for any reason be prevented from controlling the same due to an accident or the like, the release of this foot treadle immediately causes the setting of the brake, thereby locking the truck against any further movement.

Another advantage of the present invention resides in the provision of means on the uprights whereby the same are clamped in fixed laterally spaced position on the stub shafts of the axle assembly by means of brackets, whereby the entire upright structure and load supporting means can be moved forwardly away from the frame when the brackets are unclamped without dismounting any part of the frame. In this connection, I also provide a suitable cross bracing member between the uprights at the lower end thereof which is independent of the frame and which has means formed therein providing a rigid support for the hydraulic cylinder containing the actuating piston for raising and lowering the platform. If the truck is of the tilting type, this cross member will provide for conjoint tilting movement of the cylinder with the uprights in order to maintain the piston in alignment between the uprights so that the maximum effective lifting force on the load-supporting carriage is provided.

Other objects and advantages of the present invention will appear more fully from the following detailed description which, taken in conjunction with the accompanying drawings, will disclose to those skilled in the art the particular construction and operation of a preferred form of the present invention.

In the drawings:

Figure 1 is a perspective view of the truck unit of the present invention with the load-supporting means in lowered position;

Figure 2 is a corresponding view showing the load-supporting means in upper raised position;

Figure 3 is a perspective view of the truck unit showing in more detail the load-supporting mechanism;

Figure 4 is a diagrammatic view illustrating the turning radius available with a unit of this type;

Figure 5 is a top plan view of the dirigible steering means of the vehicle;

Figure 6 is a front elevational view, partly in section, of the steering mechanism shown in Figure 5;

Figure 7 is a perspective view of the steering mechanism in one of its operating positions;

Figure 8 is an enlarged view taken substantially on line 8-8 of Figure 9;

Figure 9 is a top plan view partly in section, showing the arrangement of the uprights at the forward portion of the frame;

Figure 10 is a diagrammatic view illustrating

the hydraulic connections for the lifting mechanism;

Figure 11 is a diagrammatic view of the control mechanism for operating the hydraulic lifting means; and

Figure 12 is partial elevational view of the upright structure taken substantially on line 12-12 of Figure 3.

Referring now in detail to the drawings, I have provided a truck unit indicated generally at 10, having a power unit comprising an internal combustion engine or the like mounted on the rear portion 12 of the frame of the unit and enclosed within a suitable hood 13.

A suitable dash board 14 is provided at the rear of the power unit, and forms a rear enclosure for the hood 13. This dash unit has suitable means for supporting the radiator 15 of the power unit, and provides for mounting of the steering wheel 16 thereon which operates the rear dirigible wheels 17. On the opposite side of the radiator 15 from the steering mechanism 16 there is provided a change speed control member 18 which is moved longitudinally to select the particular driving speed desired. Disposed below 25 the member 18 is the shift member 19 which operates a suitable clutch mechanism for controlling the forward or reverse movement of the vehicle, and which is provided with a throttle control portion 20 for controlling the speed of the power unit 30 in the usual manner. Disposed laterally of the control members 18 and 19 I provide the lift control arm 22, which is shown in Figure 1 in its neutral position. The member 22 is raised upwardly in the slot 23 to raise the load-carrying 35 platform indicated generally at 24, and is lowered in the slot 23 when it is desired to lower the platform.

In order to form an effective counter-balance for the load carried upon the supporting means 40 24, I provide a relatively heavy counterweight portion 25 bolted to the rear of the hood 13 on the face of the dash-board, and which extends down to the lower end of the frame. Extending rearwardly from this counterweight 25 are a pair of 45 arcuately curved side members 26 formed of cast metal or the like and of heavy section, which also serve as suitable counterweight means and in addition, afford protection means for the operator against injury due to hitting against stationary objects. The platform upon which the operator stands is indicated generally at 27, and is also a relatively heavy cast member serving as an additional counterweight. A brake actuating treadle 28 is pivotally mounted on the platform 50 27, and suitable spring mechanism at the brake itself which normally sets the brake, also serves to raise the treadle 28 to the positions shown in Figures 1 and 2. When the operator steps upon the treadle 28 and forces the same to the floor of 55 the platform 27, the brake is released, allowing free transmission of torque from the transmission to the driving axle.

The details of construction of the operating members 16, 18, 19, 20 and 22 will be found in 60 my copending application, Serial No. 94,926, filed August 8, 1936, which discloses a lift truck of the platform type which has incorporated therewith the same power unit and control mechanism as provided in the present unit.

The frame itself is of the locomotive type and has an upwardly arched rear portion which accommodates the axle assembly and steering mechanism for the rear wheels 17. This mechanism is shown more in detail in Figures 5 to 7, 70 75

inclusive, to which reference will now be made. The assembly consists of a transverse axle member 30 which is provided at its opposite ends with spindle receiving portions 32 adapted to receive the spindle 33, as shown in Figure 6, which has a tapered fit in the portion 32, and which at opposite ends is received in suitable bearing sleeves 34 and 35 carried by the trunnions 36 and 37 of the wheel spindle 38. The upper trunnion 37 of each of the wheel spindles 38 has a rearwardly extending portion 39 which, at its outer end, has a ball and socket connection 40 to the connecting member 42. The opposite end of the member 42 is connected through the turn buckle coupling 43 to a suitable connection member 44 having a socket portion 45 adapted to receive the ball 46 carried by the crank arm 47. The crank arm 47 carries a second ball member 48 extending in a direction opposite to the ball member 46 and laterally spaced therefrom which is adapted to be engaged in a suitable socket carried by the member 44 connected to the opposite wheel 17. The crank arm 47 is triangular in form, and at the apex thereof is provided with the collar portion 49 secured to the pin 50 carried in suitable bearings 52 disposed in the center bearing support portion 53 of the axle member 30. The axle member 30 is also provided with an apertured portion 54 through which extends an actuating arm 55 connected at one end by means of the ball and socket connection 56 to a crank arm 57 secured to the lower end of the pin 50 as by means of the nut 58. The opposite end of the arm 55 is connected in any suitable manner to a crank arm 60 keyed for conjoint rotation with the shaft 62 which extends vertically upwardly through the truck at one side of the power unit, and just forwardly of the dash-board 14. At its upper end the shaft 62 is connected through suitable reduction gearing to the shaft 63 of the steering wheel 16 whereby rotation of the wheel 16 causes predetermined rotation of the shaft 62 for rotating the crank 60. This in turn moves the arm 55 longitudinally to rotate the crank 57, thereby rotating the pin 50. Rotation of the pin 50 results in corresponding rotation of the crank plate 47, which produces longitudinal swinging movement of the members 44, and consequently of the associated members 42, for rotating the arms 39 about the pins 33 as a center. This in turn produces rotation of the wheel spindles 38 in the same direction about the pins 33 to produce the desired turning movement. It will be noted that by reason of the overlapping arrangement of the portions 44 of the steering arms and the relationship of the balls 46 and 48 with respect to the axis of rotation of the plate 47, a differential steering movement is provided, which results in conjoint turning movement of the wheels 17 as shown diagrammatically in Figure 4. This differential movement causes the inside wheel to turn through a greater arc than the outside wheel of the truck, and consequently produces a sharper turning angle than could be provided by the conventional steering mechanism in which the two steering spindles are cross connected in the customary manner.

This steering action is under the direct control of the operator standing upon the platform 27 so that he may guide the vehicle along aisles and around corners with the greatest facility. This also allows the vehicle to discharge its load at right angles to the aisle by reason of the fact that the rear end of the truck is capable of swinging movement about a center that is disposed

adjacent to one of the front wheels of the truck.

This action can be better considered in connection with Figure 4 in which an intersecting aisle is indicated at 70. The truck in turning about the aisle swings about a center located at the point X, which is adjacent to and in line with the axis of the front driving wheels 12 of the truck. From this view it will be apparent that the truck can turn about an intersecting aisle which is of smaller width than the overall length 10 of the truck by a considerable amount. Also, the forward portion of the truck including the load carrying means 24 can be turned at right angles to an aisle or passageway by the steering movement produced by the wheels 17, whereby the 15 truck pivots about a point adjacent one of its front wheels and consequently any load carried upon the means 24 can be discharged at substantially right angles to the aisle or passageway.

The axle 30 is supported from the frame of 20 the vehicle by means of the transverse leaf springs 74 which are connected at their ends through suitable shackles to the frame of the truck and intermediate the ends are clamped to the axle member 30 by spring clamping plates 75 secured 25 over the top of suitable recesses 76 in which the springs seat by means of bolts 77. Thus, the springs are rigidly secured to the axle 30 to support the same, and are pivotally connected at their ends to the truck frame whereby the weight 30 of the truck is resiliently supported upon the axle member 30 and the wheels to provide for the desired riding characteristics for the operator standing on the platform 27.

Considering now the structure for guiding and 35 supporting the load carrying mechanism 24, reference is made to Figures 8, 9 and 12. The forward portion of the frame 10 of the truck comprises two forwardly extending arm members 80 which are banded together at their forward ends 40 by means of the cross portion 82. Suitable laterally extending flange portions 83 on the frame members 80 serve to support an axle housing assembly indicated generally at 84.

This assembly consists of a differential case 85 in which is housed the differential gear mechanism connected to the power unit 13 of the truck through a change speed transmission of the type disclosed in my aforesaid copending application, and a forwardly extending power transmitting 50 shaft which enters the drive axle assembly 50 through the housing 86.

Bolted to opposite sides of the differential housing 85 are a pair of axle housing arms 87 which, at their outer ends are provided with circumferential flange portions 88 bolted to plates 89 carried by the wheel assembly shown in Figure 9. The arms 87 are provided with mounting portions 90 which have flanges aligned with the flanges 83 and bolted thereto by means of the bolts 92. Forwardly of the arms 87 the mounting portions 90 are provided with suitable openings for receiving the stub shaft sections 93 which are rigidly secured therein and which extend through the plate 89 into the wheel assembly. 65 The stub shafts 93 serve as bearing supports for the hub portions of the wheel discs 94 so that the wheels 12 are rotatably mounted upon the shafts 93. The discs 94 on their inner faces carry suitable internal ring gears 95 which are driven from 70 pinions 96 carried by shaft sections 97 extending through the arms 87 and into the side gears of the differential mechanism within the housing 85. Suitable sealing means 98 is provided on a closure plate 99 secured to the mounting plates 75

89, and this sealing means engages the inner periphery of the rim section of the wheel to form a suitable seal for lubricant disposed between the disc 94 and the plate 99 for lubricating the gears 95 and 96. It will thus be apparent that the wheels 72 are driven through an internal gear reduction from the axle shafts, which in turn are driven from the power unit through the differential mechanism in the housing 85.

10 The mechanism for supporting the load consists generally of a pair of upright members 100 which are preferably of channel shape and are so mounted as to face each other on opposite sides of the forward portion of the frame. At 15 their upper ends, the channel members 100 are tied together by a cross member 102 which has means for receiving the upper ends of the members 100 and is rigidly secured thereto as by means of the rivets 103. At their lower ends the 20 members 100 are provided with rearwardly offset bracket portions 104 as shown more in detail in Figure 8, the lower portion of the bracket member 104 having a semi-cylindrical recess 105 therein which fits about a bronze bearing sleeve 25 106 secured on an enlarged portion 107 of the spindle shaft 83. In order to secure the uprights on the shaft portion 107 a suitable bearing cap 108 is provided, which fits about the other half of the sleeve 106 and is rigidly secured to the portion 104 of the members 100 by means of the cap 30 bolts 110. Above the portion 104 at the rear of the upright members 100 there is provided a flange 112 which extends rearwardly from the members 100 above the frame members 80, and 35 which is adapted to receive suitable bolts for securing thereto a cross head member 113 shown in more detail in Figures 9 and 12. A series of bolts 114 extend through the flanges 112 and through lateral flange portions of the cross member 113 whereby the cross member is rigidly secured to the uprights 100, but is out of engagement with the frame 80 and any portion of the axle assembly 84. The cross member 113 has a forwardly extending portion 115 which projects 40 into the space between the lower ends of the uprights and is provided with a suitable cylindrical recess or flange portion 116 adapted to receive the lower end of a hydraulic cylinder 117 which forms the actuating means for the load-supporting mechanism.

45 50 The members 100 as stated heretofore are channel-shaped in cross section, thereby forming a pair of opposite facing guide surfaces 118 which are spaced apart a distance such as to receive the rollers 119 of the load supporting carriage. This carriage consists of frame members 120 having upper and lower journal supports 122 and 123 which carry suitable pins or stub shaft sections 124 upon which the rollers 119 are rotatably mounted. The journal sections 122 and 123 are preferably formed as split clamped sections forced together as by means of the bolts 125. At its forward end the frame portions are 55 tied together by means of a cross plate 126 which is secured to coplanar flange faces 127 carried upon each of the frame portions. The flange sections 127 terminate at their outer lateral edges in outwardly extending portions 128, thereby serving to hold the plate in fixed position therebetween, and to secure the frame portions 120 in properly spaced position. Suitable countersunk bolts 130 serve to secure the plate 126 to the forward flanged portions of the frame portions.

60 Extending transversely between the flanges 128

of the frame portions is a cross shaft member 132 which, as more clearly shown in Figure 3, is provided with a central bearing supporting bracket 133 riveted or otherwise suitably secured to the face of the plate 126. The shaft 132 serves as a guiding means for the L-shaped finger members 134 which have their vertical portions extending upwardly on the plate 126, and are provided with suitable elongated openings 135 for providing limited relative movement between the fingers and the cross shaft 132. Disposed below the shaft 132 and rigidly secured to the face plate 126 is a transverse bar 136 of rectangular cross section, which serves as a load supporting means for transferring the load from the finger members 134 to the plate 126, and hence to the frame portions 120. The rear faces of the vertical portions of the fingers 134 are provided with elongated rectangular cutouts 137 whereby the fingers may have slight relative movement with respect thereto. When a load is disposed upon the forwardly extending portions 138 of the fingers 134, the fingers move downwardly until the upper edges of the cutouts 137 engage the top surface of the bar 136. This transfers the load to the plate 126 and because of the relatively long bearing engagement below the bar 136 of the fingers 134 against the face of the plate 126, no tendency toward cocking movement of the upper end of the fingers outwardly of the plate 126 is provided.

65 Preferably, the plate 126 is provided at its upper edge with a forwardly extending transverse flange 140 which overhangs the upper ends of the fingers 134. The plate 140 is provided with a plurality of spaced openings 142, and the upper edges of the fingers 134 are provided with corresponding recesses 143. By the provision of this structure, the fingers 134 can be adjusted transversely along the shaft 132 and held in adjusted position by means of pins 144 which extend down through the flange 140 and engage in the recesses 143 to align the fingers beneath the respective openings 142. The pins are connected to the plate 126 by means of chains 145 secured at one end to the pins 144 and at the opposite end to suitable securing means 146 mounted on the plate 126. By this lateral adjustment of the fingers 144 it is possible to space the fingers so that they will fit under skids of varying dimensions.

70 75 By reason of the vertical spacing of the rollers 119 and their mounting within the guide surfaces 118 of the members 100, no cocking or binding of the load supporting means is possible within the members 100, and smooth vertical movement of the load-supporting carriage formed by the frame portions 120 and the plate 126 is assured.

In full lowered position, the load-supporting carriage is in a position relative to the members 100 as shown in Figures 1 and 8. In such position, the forward portions 138 of the finger members 134 rest upon the ground surface or floor indicated at 150. This positions the fingers so that they may be readily inserted under skids, crates, or other containing means whereby forward movement of the truck will move the forward portions 138 of the fingers into position to support the load thereon.

80 85 The frame portions 120 are each provided with a re-enforced portion 152 shown in Figure 9, which portions are apertured as at 153 to receive suitable means for securing the tension members 154 thereto. These members may be secured to the portions 152 of the frame by means of the tie bolts 155 and the nuts 156, as clearly shown in Figure 8.

The tension members preferably comprise chains of the sprocket type which have their intermediate portions trained over sprocket wheels 158, as clearly shown in Figure 3. The opposite ends of the chains 154 are secured to a cross member 160 which is bolted, riveted or otherwise rigidly secured to the rear face of the members 100 intermediate their ends, as indicated in Figures 1 and 2. The member 160 is provided with re-enforced portions 162 and the ends of the chain are provided with suitable tie bolts extending through the portions 162 and secured thereto by means of suitable nuts. Thus, upon vertical movement of the sprocket wheels 158 the chains 154 are tensioned to lift the frames 120, and consequently the plate and finger assembly or load-supporting means 24, to raise the load along the uprights 100.

Considering now in detail the upright construction in relation to the load-actuating means, the cylinder 117 at its lower end is provided with the inlet connection 170 which is connected to a suitable boss 172 formed at the bottom of the cross member 113. This inlet connection supplies fluid under pressure to the lower end of the cylinder 117 through the port 173, as will be described in detail hereinafter. Disposed within the cylinder 117 is a piston member 174 which is adapted to have reciprocating movement therein, and which is provided with a connecting rod 175 extending centrally upwardly through the cylinder 117, and having at its upper end a suitable cross head 176 which is provided with oppositely extending shaft portions 177 upon which the sprocket wheels 158 are mounted. Bolted to the upper surface of the cross head 176 is a plate member 180 having laterally extending wing portions 182 which extend into the channel formed in the uprights 100, and move upwardly therein upon upward movement of the piston to a position such as shown in dotted lines in Figure 12. This limits the upward movement of the piston by engagement of the wings 182 with the under surface of the cross member 102 at the upper end of the uprights 100.

The upper end of the cylinder 117 is held in fixed position between the uprights 100 by means of a clamping yoke 183 extending about the cylinder and secured to the cross member 160 whereby the cylinder is rigidly positioned between the uprights and rotates conjointly therewith about the spindle shaft sections 101. The cylinder is closed at its upper end by a cap plate 184 bolted, welded, or otherwise secured thereto, which plate also forms a guide for the upper end of the piston rod 175.

It will thus be apparent that by the admission of fluid under pressure through the port 173 to the lower end of the cylinder, the piston 174 will be raised, which in turn will raise the cross head 176 and cause the shortening of the tension chains 154 between the frames 120 and the sprocket wheels 158 resulting in raising of the load-supporting fingers 134 at a rate substantially twice the rate of movement of the piston.

Adjacent its upper end the cylinder 117 is provided with an outlet port 186 which is connected through the coupling 187 to the upper end of a reservoir 188 secured by means of a suitable bracket 189 and yoke 190 to the rear of the cylinder 117. The reservoir 188 has an outlet connection 192 which leads thru the flexible conduit 193 to the exhaust side of the oil pump 194 secured to and supported at one side of the motor or power unit within the hood 13. A suitable T connection 195 is provided intermediate the ends of the exhaust line 193, and is connected to the outlet side

of a control valve assembly 196 through the elbow 197. The high pressure outlet 198 of the pump assembly 194 is connected through the flexible conduit 199 to the inlet port 200 of the control valve 196. From the control valve 196 an outlet connection 202 is provided for conducting fluid under high pressure through the line 203 to the inlet connection 170 leading to the inlet 172 at the lower end of the cylinder 117.

The valve 196 is controlled by means of the control lever 22 mounted on the dash-board of the vehicle and having the forwardly extending motion transmitting rod 224 which is connected to a suitable rock shaft 204 supported on the side of the frame 10 of the truck by means of the bracket 222. A suitable crank arm 206 also secured to the rock shaft 204 has a motion transmitting rod 207 which extends forwardly to the crank arm 208 mounted on a shaft 209 secured to the front axle assembly 84.

The crank 208 is in the form of a bell crank having the forwardly extending arm 210 which is provided with a slotted portion in which is carried a pin 212 extending transversely across the lower end of a rod 213. The rod 213 is guided for vertical movement at its lower end in a suitable opening 214 in the cross member 113, and extends upwardly through the member 160 to an adjusting coupling 215 disposed above the member 160 adjacent the rear portion of one of the uprights 100. A second rod 216 is rigidly connected to the coupling 215, and at its upper end is guided for vertical movement in an offset portion 217 formed at the rear of the cross member 102 between the upper ends of the uprights. The rod 216 is threaded for a considerable distance adjacent its ends and carries thereon adjustable nuts 218 and 219 which may be moved longitudinally with respect to the rod 216 by threading the same upwardly or downwardly. The nuts 218 and 219 form automatic stop means for limiting the movement of the cross head 176.

The operation of this stop means is produced by means of a fork 220 carried on the rear face of one of the wings 182 of the member 180 secured to the upper portion of the cross head 176. When the cross head moves to its upper limiting position the fork 220 engages beneath the nut 218 on the rod 216 and raises the rod vertically with respect to the guides 160 and 217.

This results in counter clockwise rotation of arm 210 and shaft 209, which in turn moves the rod 207 rearwardly rotating the shaft 204 mounted on bracket 222. As a result, the arm 225 is rotated in a counter clockwise direction which forces the control valve plunger 223 for the valve 196 into position to by-pass the fluid back into the inlet side of the fluid pump, and thereby maintain the fluid within the cylinder 117 from escaping. This rotation of arm 225 also results in rearward movement of rod 224 which is connected at its opposite end to a bell crank 226 carried by the bracket 227 bolted to the dash board 14 adjacent the forward end of the operator's platform. The opposite end of the bell crank 226 is connected through the motion transmitting rod 228 to the pivot 229 of the lever 22.

This lever is mounted at its forward end on a pivot shaft 230 carried by a bracket 232 mounted on the inner face of the dash-board 14 in alignment with the bracket 23 which provides the slot in which the lever 22 reciprocates. The rearward movement of the rod 224 results in downward movement of the rod 228, moving the

lever 22 in a clockwise direction about its pivot 230 into the neutral position shown in Figure 11.

When it is desired to lower the load-supporting mechanism, the lever 22 is rotated in a counter-clockwise direction from its neutral position to its lowered position, which results in rearward movement of the rod 224 from the neutral position into a position to connect the end of the lift cylinder with the inlet side of the fluid pump. This allows the load supporting mechanism to move downwardly under the influence of gravity to a point where the fork 220 engages the nut 219. This moves the shaft 213 downwardly which rotates the arm 208 in a clockwise direction, moving the rod 207 forwardly and thereby producing clockwise rotation of shaft 204. As a result, the arm 225 moves the plunger 223 of the valve 196 back to neutral position, and prevents further escape of fluid from beneath the piston in the lift cylinder. At the same time, this arm produces a forward motion of rod 224 which, through bell crank 226, raises the rod 228, and consequently raises the lever 22 to its neutral position about pivot 230.

It is thus apparent that if the operator should move the control lever 22 into either of its operative positions and then leave the truck unattended, the mechanism will not be subjected to any damage due to the fact that the automatic stops controlled by rods 213 and 216 will provide for shifting of the control lever back to neutral position when the load-supporting means moves into either of its limiting positions. It is also possible in the present construction for the operator to raise, stop or lower the load-supporting means 24 during any part of its movement by means of the control member 22 which is instantly available for this purpose.

It will be noted that the uprights 100, mounted in the manner shown in Figures 8 and 9, are freely rotatable with respect to the truck frame and axle assembly about the portions 107 of the shaft sections 93. In some cases it is desirable that these uprights be rotatable as, for example, in a tilting and tiering mechanism such as disclosed and described in my co-pending application, Serial No. 190,714, filed February 16, 1938, which is directed more particularly to a tilting truck of this type. For a straight lift truck or tiering truck, however, it is desirable that the uprights be maintained in fixed vertical position in order that the load may be carried properly when no tilting action is required. Since it is impractical for purposes of standardization of the chassis of this type of truck for various types of tiering mechanisms to provide for rigid connection of the lower ends of the uprights to the truck frame or axle, I preferably employ other means for maintaining the uprights in fixed position. It will be apparent that with the construction provided, as shown clearly in Figure 8, all that is necessary for removal of the entire load-supporting and guiding mechanism is the removal of bearing caps 109 from the portions 104 of the uprights 100. When this has been accomplished, the entire assembly can be taken off from the front end of the truck without any other adjustments outside of the disconnection of the hydraulic parts by which fluid is supplied to and conducted from the hydraulic actuating mechanism carried by the uprights. This is of distinct advantage where a large variety of tiering and tilting mechanisms are required for various operating conditions and it is not desired to provide a special chassis for

each mechanism. In other words, the standardization of the frame, chassis, power unit and control assembly for trucks of this general type results in the lowering of the cost of the unit due to the mass production of these standardized parts and the specialized production of only a small portion of the complete assembly.

In order to provide for positive support for the uprights I provide suitable bracing members 240 which extend rearwardly from the upper ends of the uprights 100 and are secured at their lower ends to the rear portion of the frame 10 of the unit. These members 240 may comprise cylindrical rods of adequate cross section which, at their lower ends, are pivotally connected to the frame on opposite sides of the power unit and extend through suitable slots 242 formed in the hood 13 of the vehicle upwardly toward the upper ends of the uprights 100. At their upper ends the members 240 are secured in suitable arms 233 which are rotatably mounted upon a transverse shaft 234. The shaft 234 is mounted in suitable brackets 235 extending rearwardly from the rear face of the uprights 100 and secured thereto in any suitable manner, such as by welding, riveting, bolts or the like. The rods 240 may be adjustable in length or may be threaded into and out of the arms 233 in order to insure positive control of the position of the uprights 100. It will thus be apparent that the uprights are supported both laterally and vertically in fixed position, the vertical support being formed by the mounting of the uprights about the shaft sections 107 and the lateral support of the uprights being obtained by the cross members 102 and 160 and arms 240. This insures that the load carried upon the load-supporting means 24 will never have any possibility of throwing the uprights either forwardly or rearwardly, which might endanger the operator or produce possible damaging of the truck.

It is therefore apparent that I have provided a truck structure of the disclosed type in which a standardized chassis and frame may be employed, and which is so designed that any desired type of load-supporting means may be mounted at the forward end thereof without requiring any modification of either the frame or chassis. Also, by reason of the present construction, it is possible to raise and lower relatively heavy loads due to the novel arrangement of the fingers and their support upon the load carrying frame.

The present design is of great advantage because of its simplicity and ease of construction and assembly, as well as economy in the number of parts employed and the cost of producing these parts.

I am aware that a number of the details of construction illustrated in the present disclosure may be varied slightly without in any way departing from the underlying principles disclosed in the present invention, and I therefore do not intend to be limited except as defined by the scope and spirit of the appended claims.

I claim:

1. In an industrial truck having a frame provided with an internal gear driving axle assembly at its forward end including drive wheels journalled on dead stub shafts, a pair of upright members rotatably mounted at their lower ends on said stub shafts inwardly of the wheels, a cross head between said members at their upper ends, and bracing means pivotally connected at one end to the rear of said frame and at the oppo-

site end to said upright members intermediate their ends for controlling the vertical position of said members.

2. In an industrial truck having a frame provided with a driving axle assembly at its forward end including driving wheels and a power unit at its rear end, a pair of guide members, means rotatably supporting said members at their lower ends on said assembly coaxially of said wheels, 10 said means including split bearing journals providing for forward removal of said guide members from said assembly, load actuating means supported between said members and rotatable therewith, a load supporting carriage movable vertically in said members and controlled by said actuating means, and brace means connected between the rear portion of said frame and the upper portion of said guide members.

3. In an industrial truck of the class described, 20 a frame, a front driving axle under said frame including a pair of wheels supporting stub shafts, a pair of channel-shaped uprights secured to said shafts, bracing means between the upper end of said uprights and the rear portion of said frame, 25 a hydraulic cylinder supported at its lower end between said uprights, a load supporting carriage comprising vertically spaced rollers engaging in trackways in said uprights and including a vertical plate disposed in a plane forwardly of said uprights, L-shaped fingers adjustably secured to said plate and having the forwardly extending portions thereof engageable with the floor in lowered position of said carriage, means allowing limited vertical movement of said fingers relative 30 to said plate, and means reciprocatory in said cylinder and connected to said carriage for raising the same upon admission of fluid under pressure to said cylinder.

4. In an industrial truck of the class described 40 having a frame, a front driving axle secured to the front end of said frame and having two dead axle spindles, driving wheels freely journaled on said spindles, drive shafts extending from said axle into said wheels including internal gear means for driving the same, a pair of load supporting and 45 guiding members rotatably secured at their lower ends about said spindles inwardly of said wheels in such manner as to be removed forwardly of the axle, and bracing means pivotally connected between the upper end of said members and the rear portion of said frame.

5. In an industrial truck of the class described, 50 a frame, an axle housing supported at one end of said frame, stub shafts carried by said housing, drive means in said housing, wheels mounted on the stub shafts of said housing for supporting said frame and adapted to be driven from said drive means, a pair of channel-shaped uprights, and means for detachably securing said uprights 55 to said stub shafts inwardly of and adjacent said wheels, said securing means being so arranged that said uprights are attached to and removed from the outer side of said housing.

6. In an industrial truck, a frame, a power 60 unit supported on said frame, a drive axle mechanism at one end of said frame driven from said unit and including an axle housing having dead axle shafts and driving wheels mounted at the extremities of said shafts, a pair of channel-shaped 65 uprights, means for clamping the rear faces of said uprights to said shafts adjacent said wheels, and means secured between said frame and said uprights for maintaining said uprights in predetermined position.

7. In an industrial truck, a frame, an axle 70

housing assembly secured to the forward portion of said frame including a stub shaft having means for rotatably maintaining driving wheels thereon, a pair of channel-shaped uprights having semi-cylindrical bearing portions projecting from one edge thereof, cap means for securing said bearing portions about a portion of said stub shaft intermediate said wheel and said frame with the web of said upright projecting forwardly of said frame, and means secured between said uprights 10 at the lower end thereof for supporting a hydraulic cylinder in vertical position between said uprights.

8. In an industrial truck, a frame having a low forwardly extending front portion and an upwardly arched rear portion, a front axle assembly including a differential housing having drive shafts extending outwardly thereof above said frame, a pair of stub shafts on said frame forwardly of and parallel to said drive shafts, wheels rotatably 15 mounted on the outer ends of said stub shafts and having enclosed gear means driven from said drive shafts, a pair of channel-shaped uprights disposed on opposite sides of the front end of said frame, and detachable means for rotatably 20 securing the rear edges said uprights adjacent their lower ends to said stub shafts in such manner that said uprights may be removed forwardly 25 of the axle assembly.

9. In an industrial truck, a frame having a low 30 forwardly extending front portion and an upwardly arched rear portion, a front axle assembly including a differential housing having drive shafts extending outwardly thereof above said frame, a pair of stub shafts on said frame forwardly of and parallel to said drive shafts, wheels 35 rotatably mounted on the outer ends of said stub shafts and having enclosed gear means driven from said drive shafts, a pair of channel-shaped uprights disposed on opposite sides of the front 40 end of said frame, means for rotatably securing said uprights adjacent their lower ends to said stub shafts, and a load supporting means mounted for vertical movement in said uprights.

10. In an industrial truck, a frame having a low 45 forwardly extending front portion and an upwardly arched rear portion, a front axle assembly including a differential housing having drive shafts extending outwardly thereof above said frame, a pair of stub shafts on said frame forwardly of and parallel to said drive shafts, wheels 50 rotatably mounted on the outer ends of said stub shafts and having enclosed gear means driven from said drive shafts, a pair of channel-shaped uprights disposed on opposite sides of the front 55 end of said frame, means for rotatably securing said uprights adjacent their lower ends to said stub shafts, and hydraulic lift means supported between said uprights above the front end of said frame.

11. In an industrial truck, a frame having a low forwardly extending front portion and an upwardly arched rear portion, a front axle assembly including a differential housing having drive shafts extending outwardly thereof above said frame, a pair of stub shafts on said frame forwardly of and parallel to said drive shafts, wheels 65 rotatably mounted on the outer ends of said stub shafts and having enclosed gear means driven from said drive shafts, a pair of channel-shaped uprights disposed on opposite sides of the front 70 end of said frame, means for rotatably securing said uprights adjacent their lower ends to said stub shafts, and means connected between the upper end of said uprights and said arched 75

portion of said frame for holding said uprights in predetermined position on said stub shafts.

12. In an industrial truck having a frame, an internal gear drive axle assembly at one end thereof, a pair of uprights having their lower ends rotatably mounted on said assembly, a load supporting carriage guided for vertical movement in said uprights and including a vertical plate disposed in a plane forwardly of the up-

rights, a bar rigidly secured across the face of the plate, L-shaped fingers mounted for limited vertical movement on the face of the plate and adjustable laterally thereof, and means in the fingers receiving said bar and adapted to abut thereagainst to transmit the load from said fingers to said carriage.

ELMER J. DUNHAM.
